UNITED STATES PATENT OFFICE.

SERN MADSEN, OF CLINTON, IOWA, ASSIGNOR TO CURTIS COMPANIES, INCORPORATED, OF CLINTON, IOWA.

WINDOW-SASH-STILE MACHINE.

Application filed February 4, 1924. Serial No. 690,460.

My invention has to do with a machine for manufacturing window stiles.

Modern window stiles have in their outer faces (referring to the faces farthest from the glass pane) a hole to receive a sash cord knot, a comparatively narrow groove communicating therewith and extending longitudinally of the stile toward the top thereof and communicating with a similar wider groove. These grooves receive the sash cord and the wider groove is to receive the sash cord pulley when the sash is in its upper position. The inner face of the sash, that is to say that which receives the pane of glass, has the rabbet for the pane of glass and the mold which gives to the window sash a better appearance.

It is the purpose of my invention to provide a machine which will bore the holes mentioned, cut the grooves, dress the outer face and mould the inner face of the stile in a series of operations all of which are automatically performed.

More particularly, in this connection, it is my purpose to provide a machine of the kind under consideration having a hopper in which the sash stock previously dressed on the front and rear faces and previously passed through the tenoning and mortising machines is placed. This machine has means for boring the lowermost piece of stock in the hopper, then pushing out the lowermost piece of stock, subjecting it to saws or cutters which cut the narrow and wide grooves, then further advancing the stock and dressing the inner and outer faces.

It will be noted that I have called the face on the inside of the window the front face and the face on the outside of the window, the rear face for convenience in distinguishing from inner and outer faces in this specification.

A further purpose of my invention is to provide novel mechanism for accomplishing the boring, grooving, cutting and dressing operation and for synchronizing these various operations.

Still another purpose is to provide such a machine arranged with pairs of units, whereby rights and lefts may be cut and dressed at the same time, and in which by cutting rights and lefts at the same time, I am able to simplify instead of doubling the machinery necessary and am enabled to

handle and store the stiles in pairs with a minimum number of movements and a minimum amount of work.

For convenience, I refer to the hopper end of the machine as the rear end.

With these and other objects in view, my invention consists in the construction, arrangement and combination of the various parts of my window sash stile machine, whereby the objects contemplated are attained, as hereinafter more fully set forth, pointed out in my claims, and illustrated in the accompanying drawings, in which:

Figure 1 shows a side elevation of my improved machine.

Figure 2 shows a top or plan view of the rear portion of the machine having the hoppers, the boring and groove cutting mechanisms, and part of the stock advancing mechanisms.

Figure 3 shows a vertical, sectional view taken on the line 3—3 of Figure 2.

Figure 3^a is a detail, sectional view of part of the frame and drill bed.

Figure 4 shows a vertical sectional view taken on the line 4—4 of Figure 2, illustrating the variable speed mechanism for the boring and groove cutting means.

Figure 5 is a vertical, sectional view taken on the line 5—5 of Figure 2.

Figure 6 is a transverse, vertical sectional view taken on the line 6—6 of Figure 5, illustrating the means for pushing the stock out of the hopper.

Figure 7 shows a transverse, vertical sectional view taken on the line 7—7 of Figure 3 and illustrating particularly the boring mechanism.

Figure 8 shows a transverse, vertical sectional view taken on the line 8—8 of Figure 2.

Figure 9 is a vertical, sectional view taken on the line 9—9 of Figure 8.

Figure 10 is a horizontal, sectional view taken on the line 10—10 of Figure 8, illustrating part of the operating mechanism for the groove cutters.

Figure 11 is a vertical, sectional view taken on the line 11—11 of Figure 3, illustrating the clutch for the cam disc which actuates the boring and groove cutting members.

Figure 12 is a detailed, side elevation of a part of the machine illustrating the

"speed up" mechanism for advancing the stock from the boring and grooving mechanism to the sticking mechanism, whereby the inner and outer faces of the stile are dressed.

Figure 13 is a transverse, sectional view taken on the line 13—13 of Figure 12.

Figure 14 is a vertical, sectional view taken on the line 14—14 of Figure 2.

10 Figure 15 is a top or plan view of the front portion of the machine.

Figure 16 is a detailed, top view of a portion of the operating mechanism.

15 Figure 17 is a vertical, sectional view taken on the line 17—17 of Figure 15.

Figure 18 is a transverse, vertical sectional view taken on the line 18—18 of Figure 16.

20 Figure 19 is a front end view of the machine partly in section.

Figure 20 is a vertical, transverse, sectional view taken on the line 20—20 of Figure 17.

25 Figure 21 is a perspective view of a window sash.

Figure 22 is a sectional view through the upper portion of one of the stiles.

30 Figure 23 is a transverse, sectional view taken on the line 23—23 of Figure 22; and

35 Figure 24 is a view similar to that shown in Figure 23 of the stile after the boring and grooving operations and after the dressing of the inner and outer faces.

For facilitating the understanding of the construction and operation of my machine, I will briefly outline the steps in such operation.

40 The stock is placed in the two hoppers manually or otherwise, as may be desired, after the stock has come from the mortising and tenoning machines.

45 The first operation involves the boring of the hole for the sash cord knot. Immediately thereafter the pusher bar engages the lowermost member in the pile of stile stock in the hopper and pushes it forward in the machine for the grooving operations, whereby the narrower and wider grooves are cut. The stock is then advanced by a "speed up" mechanism to the "sticking" unit whereby the inner and outer faces of the stock are dressed and trued, after which the stock is discharged from the machine.

55 The stock is stationary during the boring operation and is advancing during the grooving and "sticking" operations. The movement of the stock is continuous though variable after the stock leaves the boring means.

60 It will be understood that the machine consists of a series of units, to-wit: hoppers, boring means, grooving means, "speed up" mechanism and "sticking" units, and that these units are arranged in pairs on opposite sides of the machine, so that right and left

stiles are simultaneously bored, right and left stiles are simultaneously grooved, and right and left stiles are simultaneously dressed in the "sticking" units.

The units are the same except in the fact that they are arranged for cutting rights and lefts and are arranged slightly differently in the machine with relation to the sides thereof.

70 Before describing the machine and its operation, I will refer to the window sash illustrated in Figures 21, 22, 23 and 24, where I have used the reference numeral 10 to indicate generally the stiles of the sash.

75 The stiles of the top sash and bottom sash are slightly different in respects, which are not now important.

80 It will be noted that I have called the face A the outer face, the face B the inner face, the face C, which is on the outside of the window when installed, the rear face, and the face D the front face. The use of these reference characters will be convenient in referring to the operation of the machine.

85 In the outer face of each stile near the upper part thereof, it is the custom to bore a hole 11 to receive the sash cord knot. This hole has its axis inclined slightly upwardly, as shown for instance in Figures 21 and 22. Communicating with the hole and extending upwardly longitudinally of the outer face of the stile 10 is a comparatively narrow groove 12 to receive the sash cord, which 90 communicates with a longitudinally upwardly extending wider groove 13 to receive the sash cord and also to receive the sash cord pulley, which projects into the channel where the stile of the finished sash travels.

95 In the completing of the stile, the inner face B thereof is provided with a rabbet 14 for the pane of glass 15 and the putty 16 and with a mold 17, rib 18 and quirk 19. The dressing of the inner face varies somewhat in different stiles.

Frame.

100 The frame of my machine includes a base 20, shown for instance in Figure 1, and a plurality of upright members 21 suitably located and arranged to support the mechanism.

110 The rear part of the machine is provided on each side with a table 22, which supports the stock during its movement from the hopper to the sticking units. The tables are spaced from each other laterally, so as to leave ample room between them for the mechanism hereinafter referred to.

Hopper.

115 On each side of the machine at the rear end thereof, there is provided a hopper. The hopper has an inner wall 23 with an

angle iron 24 at its forward end having an outwardly laterally extending flange 24^a (see Figures 1 and 2), which forms the front end of the hopper.

5 The flange 24^a is cut away at its lower end as at 24^b (see Figure 1) a sufficient distance above the table 22 to permit the bottom stile 10 of the stile stock in the hopper to be slid forwardly from the hopper.

10 The rear wall of the hopper is formed by an angle iron 25, having one flange extending transversely of the machine and one flange extending longitudinally of the machine in a plane parallel with and spaced from the outer face of the wall 23, as shown for instance in Figures 1 and 2. The angle iron frame member 25 of the hopper is adjustably mounted on the table 22.

15 Adjustably mounted on the table 22 near the front end of each hopper and spaced from the wall 23 is an upright bar 26 shown for instance in Figure 1.

20 The transversely extending flange of the angle iron frame member 25 terminates above the table 22, as shown in Figure 6, for allowing free movement of the stock pusher bar hereinafter referred to.

25 The frame members 25 and 26 are mounted for lateral adjustment and longitudinal adjustment on the machine, in the following manner:

30 An angle iron 27 is mounted on the table 22 spaced from the wall 23 with a horizontal flange resting on the table and extending away from the wall 23, as shown in Figures 1 and 6, and with a vertical flange. In the horizontal flange are laterally elongated slots 28 to receive locking screw bolts 29, which are screwed into suitable holes 30 in the table 22.

35 The angle iron 27 may be thus adjusted laterally by loosening the screw bolts 29, adjusting the angle iron, and then fastening the screw bolts.

40 The bar 26 and the outer flange of the angle iron 25 are provided with plates at their lower ends, as at 31 (Figure 6), which rest on and may slide upon the vertical flange of the angle iron 27. A screw bolt 45 or the like 32 is mounted in each plate and projects outwardly. Mounted on the screw bolt is a yoke 33, having one arm bearing against the bar 26 and one arm against the vertical flange of the angle iron 27, (in the case of the frame member 26). In the case of the angle iron 27 one arm of the yoke member bears against the outer flange of the angle iron 25 and the other against the vertical flange of the angle iron 27.

45 A nut 34 with a handle 35 thereon is mounted on the outer end of the screw bolt 32, as shown in Figure 6, and it is seen that by tightening the nut, the members 25 or 26 may be clamped to the angle iron 27 in various positions of longitudinal adjust-

ment thereon. This longitudinal adjustment of the angle iron frame member 25, forming the rear end of the hopper is important in adjusting the hopper for receiving stock of different lengths.

50 It is thus obvious that each hopper is adjustable for different widths and different lengths of stock.

Boring mechanism.

75 The lower piece of stock is bored for the hole which receives the sash cord knot while lying at the bottom of the pile in the hopper. I will now describe the boring mechanism and in connection therewith some of the 80 power and operating mechanism of the machine.

Suitably supported on the base 20 near the rear end of the machine is a power unit, such for instance as the electric motor 36, 85 which drives a longitudinally arranged shaft 37, shown in Figures 1 and 3 mounted in bearings 38 and 39.

90 On the shaft 37 is a belt pulley 37^a shown for instance in Figures 1, 3 and 7, from which the boring drills are rotated. The drills for boring the holes 11 are supported in the following manner: A frame 37^b, the general shape of which is indicated in Figure 2, rests on certain of the uprights 21 with its ends just under the table 22. Between the frame 37^b and the tables 22 are filler blocks 37^c, shown in Figure 7. On the rear part of the frame 37^b are mounted beds 37^d, forming generally the shape of a 100 forwardly opening V. The beds 37^d have tongues 372 extending downwardly into slots 373 in the member 37^b. Filler blocks 374^a of various thicknesses may be selectively employed between the beds 37^d and the member 37^b for holding the drill carriages at the proper height. The drill carriages are drawn tightly against the filler blocks by means of threaded studs 374^b on which are nuts 374. Slidably mounted on the two 110 opposite beds 37^b are the drill supporting blocks 37^e, illustrated for instance in Figure 7. Each block 37^e is provided at both ends with a journal 37^f, in which is journaled a drill shaft 37^g, to which a drill 115 37^h is connected in an ordinary way.

120 Mounted on each drill shaft 37^g between the journals 37^f is a pulley 37ⁱ. A belt 37^j is extended around the lower part of the pulley 37^a and thence upwardly and around the two pulleys 37ⁱ and thence downwardly around the idler pulleys 37^k mounted on brackets 37^l for vertical adjustment. It will be thus seen that the pulleys 37ⁱ and the drill bits 37^h are rotated from the pulley 125 37^a. The blocks 37^e slide on the beds 37^d for the purpose of moving the drill bits to operative position and the sliding movement is accomplished in the following manner:

130 Pivoted at laterally spaced points on the

forward portion of the frame 37^b are rearwardly projecting arms 37^m, the rear ends of which project into suitable slots 37^a, shown in Figure 2 in the respective sliding blocks or carriages 37^e. Each arm 37^m has an inwardly projecting arm 37° carrying a roller 37^p. Springs 37^q connected with the sliding blocks or carriages 37^e normally hold the drill bits at the inner limits of their movement.

The walls 23 are provided with suitable openings 37^r (see Figure 2) for the passage of the drill bits to position for boring the lower piece of stile stock, when the drills are slid outwardly for the boring operations.

For effecting the outward movement of the arms 37^m and the consequent outward movement of the drill carriages and drills, I have provided the following means:

Suitably mounted on uprights of the main frame is a transverse shaft 37^s, having a slightly reduced portion 37^t, shown in Figure 11, upon which there is mounted for rotation the disc 37^u having a clutch face 37^v on one side. A coacting clutch member 37^w is slidably but non-rotatably mounted on the reduced portion 37^t of the shaft 37^s in position to coact with the clutch face 37^v. The clutch member 37^w is provided with an annular groove 37^x. A collar 37^y has a screw-threaded connection with the portion 37^t of the shaft 37^s as shown in Figure 11. Arms 37^z are secured to the collar 37^y by bolts 38^a and have portions 38^b projecting into the groove 37^x. Secured to the collar 37^y is a handle or the like 38^c for rotating that collar for moving the clutch member 37^w into or out of engagement with the clutch member 37^v on the disc 37^u.

If it is desired to operate the machine without operating the boring mechanism, the clutch members are disconnected, so that the disc 37^u will not rotate.

On the shaft 37^s is mounted a gear 38^d in mesh with a gear 38^e on a suitable mounted transverse shaft 37^f. (Figure 3). The shaft 38^f is operated from the shaft 49 by means of a belt 38^g traveling on a belt pulley 38^h on the shaft 38^f and a belt pulley 38ⁱ on the shaft 49.

The shaft 37 (Figure 3) extends forwardly in the machine from the motor 36 and has on its forward end the worm 40 meshing with the worm wheel 41 on a suitable mounted transverse shaft 42.

Keyed to the shaft 42 are a series of pinion gears 44, 45, 46, 47, and 48, which are used in operating the boring and groove cutting mechanisms at variable speeds.

Suitably mounted parallel with the cross shaft 42 is a jack shaft 49 shown in Figures 2 and 4. Fixed on the shaft 49 is a wide gear 50. (See Figure 2).

Slidably mounted on the gear 50 is a

sleeve 52. An arm 53 fixed to the sleeve 52 projects laterally from the side of the machine and has on its outer end a handle 54, shown in Figures 2 and 3 and used for imparting limited rotation to the sleeve 52. 70

Projecting from the sleeve 52 are parallel arms 55 between the outer ends of which is rotatably mounted an idler gear 56 on the short shaft 57. The gear 56 is in sliding mesh with the gear 50 and is designed 75 to selectively mesh with any of the gears 44, 45, 46, 47 or 48. The sleeve 52 is slid longitudinally on the gear 50 for causing the gear 56 to mesh with the various gears 44 to 48 inclusive. 80

The gear 56 stands above the gears 50 and the gears 44 to 48 inclusive, as shown in Figure 4, and may be raised for enabling it to be slid from a smaller gear of the series 44 to 48 to a larger gear thereof by tilting 85 it by means of the arm 54.

An ordinary belt tightener mechanism 58, shown in Figure 3, is provided for the belt 38^g. On the opposite sides of the disc 37^u are cams 59, which engage the rollers 37^p. 90

Before proceeding with the further description of the machine, I will briefly outline the operation of the boring drills.

Assuming that stock is in the hoppers and that the motor 36 is started, it will be 95 seen that the shaft 37 (Figure 3) will be rotated and through the worm 40 will rotate the worm wheel 41 on the shaft 42 and the shaft 42 and the gears 44 to 48 thereon. That one of the gears 44 to 48, 100 which is in mesh with the gear 56 (see Figures 2 and 4) will rotate such gear 56, which in turn imparts rotation to the wide gear 50 and the shaft 49. Rotation of the shaft 49 is imparted through the pulleys 105 38^h and 38ⁱ and the belt 38^g to the shaft 38^f and the gear 38^e thereon. The gear 38^e rotates the gear 38^d (see Figure 7) and the shaft 37^s, the clutch member 38^w and the disc 37^u. (See Figure 11). 110

The drills are rotated from the pulley 37^a by means of the belt 37^j traveling over the pulleys 37^a, 37ⁱ and 37^k.

When during the rotation of the disc 37^u, the cams 59 shown in Figure 3 and Figure 115 2 engage the rollers 37^p, the arms 37^m are reciprocated outwardly carrying with them the drill carriages 37^e, shown in Figures 2 and 7, for causing the rotating drill bits to pass through the openings 37^r into the lower stile 120 10 in the stock in the hoppers for boring the holes 11 in the right and left stiles in the respective hoppers.

As soon as the cams 59 clear the rollers 37^p, the springs 37^q withdraw the drill bits. 125

The next operation consists in sliding the lowermost stile members 10 in which the holes 11 have been bored out of the hopper, advancing them to the groove cutting members and cutting the grooves. 130

I will now describe the means for moving the stiles out of the hoppers.

Pusher bar for sliding the stiles from the hoppers.

5

Mounted on each table 22 at the rear part of each hopper is a push bar 60 (see Figures 5 and 6), having in its under side a downwardly opening slot 61. The slot is narrower at its mouth than at its upper portion as illustrated in Figure 6.

In the table below the path of travel of the pusher bar 60 is an elongated slot 62, shown in Figure 5. A block 63 has a reduced portion 64 projecting into the slot 62 as shown in Figure 6. A screw bolt 65 has a tapered head 66 received in the slot 61 in the pusher bar and has its shank extended through the block 63.

20 A sleeve-shaped nut 67 is screwed onto the lower end of the screw bolt 65 for clamping the pusher bar 60 and the block 63 together. The reduced portion 64 of the block 63 is of sufficient height to prevent binding between the pusher bar and the block 63 and the table, but to permit the pusher bar and the block 63 to be tightly locked together.

30 The nut 67 has a downwardly projecting shank 68 through which extends a pin or cross bar or the like 69 for convenience in rotating the nut 67.

35 The block 63 has a projecting arm 70 in which is mounted a shaft 71 with which is connected a reciprocating link 72. (See Figure 5.) Fixed to a shaft 73 journaled in two of the upright members 21 is an operating channel bar 74, which at its upper end is pivoted to the link 72 at 75. Mounted 40 on the gear 38^a is a roller 76 which projects into the channel-shaped operating bar 74. (See Figures 3, 5 and 7.) On the other side of the machine, a lever 74^a is fixed to the shaft 73, and is fixed to the link 72 on that side.

45 Portions of the walls of the channel-shaped operating bar 74 indicated at 78 are curved on the arcs of circles, having their centers at the center of the shaft 38^a on which the gear 38^a is mounted for a purpose, which will be later referred to.

Assuming that the parts just described are in their positions shown in Figures 3 and 5, just after the cams 59 have passed the rollers 37^a and the boring drills have been withdrawn and that the gear 38^a, (shown in Figure 5) is moving in a clockwise direction, and that the pusher bar is at the rearward limit of its movement with its forward end adjacent to the rear end of the lowermost stile 10, the further rotation of the gear 38^a will carry the operating channel bar 74 forwardly in the machine, drawing with it the link 72, the block 63 and the pusher bar 60.

The pusher bar 60 will engage the lower stile 10, sliding it forwardly on the table 22 under the flange 24^a of the angle iron 24 to position for the grooving operation.

On the forward end of each hopper, there 70 is mounted for loose vertical sliding movement a heavy weight 79, which, as shown in Figures 1, 3, 8 and 9, is hung by means of a screw bolt 80 and adjustable nut 81 thereon on a bracket 82, and is held against horizontal movement by bolts 83 extended through vertically elongated slots 84 and having washers 85 thereon.

Mechanism for cutting sash pulley grooves. 80

I will now describe the mechanism for cutting the grooves 12 and 13 shown in Figures 21 to 24 inclusive in the stile.

On each side of the machine forwardly of the hoppers, there is pivoted for sidewise swinging movement a downwardly opening A-shaped frame 86, having its arms connected near their lower ends by a cross brace or frame member 87, as shown for instance in Figure 3.

90 These frames are designed to carry at their upper ends the grooving cutters and are designed to be swung laterally for moving the grooving cutters to operative position and vice versa.

95 Supported from the frame member 87 is a gear casing 88 shown in Figures 1, 3, 8 and 10. Fore-and-aft spaced upright shafts 89 and 90 are mounted in the gear casing 88, the frame member 87, and are journaled in the upper end of the frame 86, as shown particularly in Figures 3 and 8.

100 The rearward one of these shafts carries on its upper end the grooving cutter 91, while the forward shaft 90 carries on its upper end the somewhat wider grooving cutter 92.

105 On the lower ends of the shafts 89 and 90 in the gear casing 88 are helical gears 93 and 94, both of which mesh with an idler helical gear 95, also mounted in the gear casing 88. (See Figure 10.)

110 On each shaft 90 is a belt pulley 96, which is operated in the manner hereinafter referred to.

115 It will at this time, however, be obvious that upon the rotation of the shaft 90 through the belt pulley 96, the gears 94, 95 and 93 will be rotated for rotating the shaft 89.

120 The frames 86 on the opposite sides of the machine are connected together by a powerful coil spring 97, shown in Figures 2 and 8 for instance, which yieldingly tends to hold them inwardly where the grooving cutters 91 and 92 will be out of the path of travel of the stile stock.

125 At the inner edge of each table 22 is a plate or strip or the like 98, shown for instance in Figures 1, 2 and 3, serving as a 130

guage and stop for the outer faces of the stiles, which faces are in fact the inner faces of the stile stock, as they are arranged in passing through the machine. This guage or stop strip 98 is a continuation of the inner wall of the hopper, and, adjacent the cutters 91 and 92, it is of such height that cutters may freely move laterally over it for cutting the grooves in the stile stock.

10 For accomplishing the outward lateral movement of the frames 86 and the shafts 89 and 90 and the grooving cutters 91 and 92 carried by said shafts, there is provided the following means:

15 To the forward face of the frame 37^a hereinbefore referred to which supports the arms 37^m and the boring drills, there are pivoted two downwardly hanging arms 100 as shown for instance in Figures 2, 3 and 8.

20 The lower ends of the arms 100 carry rollers 101 on pintles or short shafts 102. The lower end of each arm 100 is pivoted to a longitudinally adjustable link 103, which in turn is pivoted to one of the frames 83.

25 The periphery of the disc 37^a hereinbefore referred to is provided for a substantial portion of its length with a cam 104 adapted to travel between the rollers 101 and having its edges tapered where it first engages and finally leaves the rollers 101, as at 105 in Figures 3 and 8.

It will be noted from the showing in Figure 3 that after the disc 37^a moving in clockwise direction carries the cams 59 past the rollers 37^p (see also Figure 2) and while the roller 76, shown in dotted lines in Figure 3 and also illustrated in Figure 5, is actuating the bar 74 for operating the pusher bar and advancing the stile stock, the cams 104 will enter between the rollers 101 forcing them apart and through the links 103, swinging the frames 86 outwardly or laterally for causing the grooving cutters 91 and 92 to swing to position for cutting the grooves 12 and 13. (See Figures 2, 3, 8 and 21.)

40 Owing to their relative location longitudinally of the machine, it is obvious that the narrow cutter 91 will cut a narrow groove first and that the wider cutter 92 will subsequently engage the same piece of stock and will make its wider cut during the finishing of the cut of the groove cutting member 91.

45 It is also obvious that since the cutters 91 and 92 are withdrawn from operative position at the same time, that the wide groove 13 will be shorter than the full length of the groove cut by the cutter 91.

50 As soon as the cam 104 passes from between the rollers 10, the spring 97 will swing the frames 86 toward each other and withdraw the cutters 91 and 92 from operative position.

55 Mounted on the forward end of each angle iron 27 are two forwardly projecting press-

er springs 106 and 107 designed to yieldingly press the advancing stile stock against the guage or stop member 98. (See Figure 2).

I will now explain the reason for the curved shape of the walls 78 of the channel bar operating member 74, to which I have heretofore referred.

It is noted that during the operation of the machine, the gear 38^d, which actuates the bar 74, is in continuous operation. It may also be noted that it is desirable that the pusher bar actuating from the operating bar 74 should be stationary at its rearward limit of movement during the boring operation hereinbefore referred to. The pusher bar is left stationary on account of the curvature of the wall portions 78, which makes it possible for the roller 76 to travel approximately from the point 108 shown in Figure 5 to its position shown in full lines in Figure 5 without imparting any movement to the bar 74.

The further movement of the roller 76 upon the continuation of the rotation of the gear 38^d actuates the pusher bar 60 for advancing the stock, and this advancing movement is continued until the grooving operation is completed.

I find it desirable to give to the stock a quicker movement toward the speed-up mechanism, to which I will later refer, after the grooving operation has been completed, and this is accomplished during the downward movement of the roller 76 between the curved wall portions 78 from the position shown at 109 in dotted lines in Figure 5 to approximately the point marked 110 in said figure.

It is also desirable that the return of the pusher bar 60 should be quicker than its advancing movement in order to maintain the maximum speed of operation of the machine, and this is accomplished by the arrangement of the operating bar 74 and the gear 38^d and the roller 76, whereby the roller 76 is farther from the pivot point 73 during the advancing movement of the pusher bar 60 and substantially closer to said pivot point during the return movement of the pusher bar.

"Speed up" mechanism.

In order that the units of the machine, which operate following the operation of the boring unit may run at normal and maximum capacity, it is desirable that there be a speeding up in the movement of the stile stock following the intermittent motion from the hopper and through the grooving operation, and in the present machine, this speeding up or catching up is accomplished by the mechanism which seizes and advances the stock following the grooving operation for carrying the stock to the sticking units.

The "speed up" mechanism is especially illustrated in Figures 12, 13 and 14.

Mounted on each side of the machine on certain of the uprights 21 is a longitudinally arranged supporting bar or the like 111. The bars 111 on the opposite sides of the machine are located just below the tables 22 and are parallel with each other and carry a pair of transverse spaced shafts 112. On the ends of the shafts 112 are rollers 113, which project through suitable slots 114 in the tables 22.

It may be said that the bars 111 are mounted on the uprights 21 by means of the bolts 115 screwed into the uprights 21 and extended through vertically elongated slots 116 in said bars 111.

Below the bars 111 are projecting lugs 117 extending from the uprights 21 and having adjusting screw bolts 118 therein, as shown in Figure 13. The shafts 112 extend across the machine and are common to the "speed-up" mechanisms on the opposite sides of the machine.

The rollers 113 project upwardly through the tables 22 just enough so that the stock may travel properly on them.

The upper rollers for coacting with the rollers 113 and for gripping, holding and advancing the stock in cooperation therewith are mounted as follows:

Supported on and extending upwardly from the outer edges of the tables 22 are brackets 119 which support a transverse shaft 120 extending across the machine.

On each side of the machine arms 121 are pivoted on the shaft 120 and extend rearwardly in the machine, and arms 122 are pivoted on the shaft 120 and extend forwardly in the machine.

The arms 121 support a transverse shaft 123 extending across the machine and the arms 122 support a transverse shaft 124 extending across the machine. The shaft 123 has rollers 125 on its ends above the rearward rollers 113 and the shaft 124 has similar rollers 126 on its ends arranged above the forward rollers 113.

The arms 121 are spring-pressed downwardly in the following manner:

Screw bolts 127 are screwed into blocks 128 mounted in the inner edges of the tables 22 by means of bolts 129 and extend slidably through lugs 130 on the arms 121. Springs 131 arranged above the lugs 130 on the bolts 127 and between said lugs and the heads of the bolts exert a yielding downward pressure on the arms 121.

An adjustable stop for limiting the downward movement of said arms is provided in the screw bolts 132 mounted in the arms 121 and adapted to coact with wear plates 133 on the blocks 128.

Mounted on each arm 121 adjacent to the roller 125 thereon is a shoe 134, shown in and

Figure 12, which stands just enough above the level of the lower part of the roller 125 to clear stock traveling under such roller, but close enough to the stock, so that when the rear end of one stile passes under and 70 clears the lower side of the roller 125, the shoe 134 will drop upon such stock, as shown in Figure 12, and prevent the roller 125 from rolling over the end of the stock and tearing the edge thereof, because of the corrugated surface of the roller. 75

The blocks or strips 128 are arranged to serve as a gauge or back stop for the stock in the same manner as do the members 98 already referred to. 80

The stock before it leaves the springs 106 and 107 is engaged by springs 135, which hold it pressed inwardly against the blocks or strips 128.

The "speed up" mechanism is operated 85 in the following manner:

On the shaft 42 hereinbefore referred to and shown in Figures 1, 2, 3, 4 and 14 is a sprocket 136 in line with another sprocket 137 on the shaft 120. (See Figure 14). 90

A sprocket chain 138 travels on the sprockets 136 and 137 for transmitting rotation to the shaft 120 from the shaft 42. (See Figures 2 and 14). The chain 138 also engages an idler gear 139 on a stub shaft 95 140 arranged below the gear 137 with the stub shaft 140 above the level of the shafts 112.

On the shafts 123 and 124 are sprockets 141 and 142 shown in Figure 14. On the 100 shaft 120 are sprockets 143 and 144 (see Figures 2 and 14) which are aligned with the respective sprockets 141 and 142.

On the sprockets 141 and 143 a chain 145 travels and on the sprockets 142 and 144 the 105 sprocket chain 146 travels for transmitting rotation from the shaft 120 to the shafts 123 and 124.

On the shafts 112 are sprockets 147 shown in Figure 14. On the shaft 120 is a sprocket 110 148 and on the shaft 140 is a sprocket 149, the last four sprockets being in the same plane. A chain 150 travels around the sprockets 147 and over the sprockets 148 and 149 as shown in Figure 14. The sprockets 115 139 and 149 are idlers.

It will thus be seen that motion is transmitted from the shaft 42 to the sprocket 136 and thence through the chain 138 to the sprocket 137 and the shaft 120. From the 120 shaft 120, motion is transmitted through the sprockets 143 and 141 and the sprocket chain 145 to the shaft 123.

Similarly from the shaft 120, motion is transmitted to the shaft 124 through the 125 sprocket 144, the chain 146 and the sprocket 142.

Motion is transmitted from the shaft 120 to the shafts 112 through the sprockets 147 130 and the chain 150.

The operating mechanism for the "speed-up" mechanism and the rollers 113, 125 and 126 are so geared that those rollers advance the stock faster than the pusher bar hereinbefore referred to, and the stock advancing mechanism of the sticking unit hereinafter described.

Sticking unit.

I will now explain the construction of the sticking unit of my machine. The sticking unit is shown in Figures 1, 15, 16, 17, 18, 19 and 20.

It involves cutting devices for dressing the inner and outer faces of the stiles that have been bored and grooved and mechanism for advancing the stock past these cutting tools.

I will first explain the mechanism for receiving and advancing the stock.

At the ends of the tables 22, channel-shaped beds 151, shown in Figures 1, 17, 19 and 20, are provided arranged with the bottom of the channels slightly below the level of the tables.

Mounted on transverse shafts 152 and 153, shown for instance in Figures 1 and 17 are tumbler sprockets 154 and 155, the arrangement of the sprockets on both sides of the machine being the same, and the shafts being extended across the machine.

On each side of the machine, a conveyor chain 156 travels around the sprockets 154 and 155 through the channel of the bed 151 and around idler rollers 157.

On suitable upright members of the main frame are mounted transverse frame members 158 and 159, each substantially rectangular in outline. These frames 158 and 159 have bolted thereon on each side of the machine upwardly projecting supporting arms 160 and 161.

Mounted for vertical sliding adjustment on reduced upper ends of the arms 160 and 161 are sleeves 162 shown in Figure 17. Mounted on the reduced upper portion of each arm 160 and 161 above the sleeve 162 is a coil spring 163 held in place by an adjustable nut 164, shown for instance in Figure 17.

Formed on each sleeve 162 is a horizontal journal 165. Shafts 166 have cylinders 167 eccentrically arranged thereon and mounted in the journals 165 of the laterally opposite sleeves 162.

At each side of the machine, the frame member 168, shown for instance in Figures 17 and 20, is supported on the outer ends of the shafts 166. These frame members 168 extend longitudinally in the machine.

Supported at the lower edge of each frame member 168 is a downwardly opening channel bar or the like 169, serving as a guide for the endless chain hereinafter referred to.

Mounted at each end of each frame member 168 for sliding adjustment longitudinally of the machine is a bracket or the like 170 shown for instance in Figures 1 and 20, which at its outer end has a journal 171 70 for a transverse shaft 172. (See Figures 1, 15, 17 and 19.)

The sliding brackets or shaft supports 170 just mentioned are mounted on the frames 168 by means of bolts 173 shown 75 for instance in Figures 1 and 20 which extend through longitudinally elongated slots 174 in the members 170, so that by loosening the bolts 173, the shaft supporting bars 170 may be adjusted lengthwise of the machine. 80

Mounted in lugs 175 on the frame members 168 are adjusting screw bolts 176 (see Figure 1), for coacting with the brackets 170.

It will thus be seen that the respective 85 bars 170 support shafts 172 spaced from each other longitudinally of the machine. On the shafts 172 above the tumbler sprockets 154 are mounted tumbler sprockets 177.

On the longitudinally aligned tumbler sprockets on each side of the machine is a chain 178, the lower stretch of which travels in the downwardly opening channel-shaped guide 169.

Guide plates 179 are secured to the lower walls of the guide 169, as shown in Figure 20, by means of screws or the like 180 and overlie the channel portion of the guide, so as to support the links of the chain 178, 100 as shown in Figure 20, so that the lower stretch of said chain will be held in horizontal position during the operation of the machine.

Secured to the links of the chain 178 are 105 rubber pads 181, shown in Figures 17 and 20, which can be detachably mounted by screws 182. The chains 178 and 156 coact for advancing the stock through the sticking unit and past the dressing cutters in a 110 manner hereinafter again referred to.

Owing to the fact that there are some variations in the thickness of the stock sent through the machine, it is desirable to be able to raise or lower the upper chain 178, 115 and for this purpose, I provide the following means:

On each shaft 166 between the chains 178, there is mounted an upwardly projecting, downwardly opening U-shaped bracket or the like 184, the arms of which have journals 185 receiving the appropriate shaft 166. The brackets 184 are connected by a downwardly opening channel-shaped angle iron member 185^a, illustrated in Figures 15 125 and 20.

On each shaft 166 between the arms of the bracket 184 is mounted a worm wheel 186. A shaft 187 is journaled on the brackets 184 and is provided with worms 130

188 meshing with the worm wheels 186 and is formed at 189 to receive a wrench or the like, whereby the shaft 187 may be rotated.

It will be seen that by rotating the shaft 187 the worm wheels 186 may be rotated. These worm wheels are fixed on the shafts 166 and their rotation will be imparted to the shafts 166 for rotating said shafts.

Owing to the eccentric arrangements of the cylinders 167 on the shafts 166, the bodies of said shafts will be raised or lowered with relation to the sleeves 165 and the frame of the main machine, carrying with them the frames 168, the tumbler sprockets 177 and the chains 178.

It will be seen that the brackets 184 and the parts carried thereby will be raised or lowered with the shafts 166.

For operating the chains 156 and 178, the following means are provided:

Pivots mounted on brackets 190 on the base of the machine are the arms 191 of a forwardly extending yoke-shaped member 192. A similar yoke-shaped member with forwardly extending arms, which member is indicated by the numeral 193, and is shown in Figures 15 and 17, is mounted on the yoke 192 for adjustment longitudinally of the machine. This is accomplished by extending bolts 194 through longitudinally elongated slots 195 in the yoke 193, as shown in Figure 17, and by mounting said bolts in the yoke 192.

In the forward ends of the arms of the yoke 193, there is mounted a shaft 196, shown in Figures 1, 17 and 18.

The shaft 196 carries a sleeve 197 journaled in the arms of the yoke 193, as shown in Figure 18. The sleeve 197 has in its central portion opposite longitudinally elongated slots 198.

Clutch members comprising pins or the like 199 are extended through and fixed to the shaft 196 and project through into or through the slots 198. The sleeve 197 has loosely mounted thereon sprockets 200 and 201 of different sizes which have clutch faces 202 adapted to coat with the pins 199 when the shaft 196 is slid longitudinally in the sleeve 197.

The shaft 196 is pivoted by means of a lever 203, shown in Figures 15 and 18, at one end and having a portion projecting into a groove or slot 204 in said shaft.

It will be seen that by means of the lever 203 the shaft 196 may be moved to neutral position or to its positions where it is locked to the sprocket 200 or the sprocket 201 as may be desired.

The shaft 196 is operated from the shaft 42 by means of a sprocket chain 205 traveling on a sprocket 206 on the shaft 42 and a sprocket 207 fixed on the sleeve 197 and shown in Figures 15, 16 and 18.

On the rearward shaft 172 are laterally

spaced sprockets 208, which are aligned with similar sprockets 209 on the shaft 153 and with the respective sprockets 200 and 201. A chain 210 (Figure 19) travels around the sprocket 200 and the upper aligned sprocket 208 and over the front face of the aligned sprocket 209, and a similar chain 211 travels over and around the sprocket 201 and around its aligned sprocket 208 and over the front face of its aligned sprocket 209, as illustrated in Figure 17.

It will thus be seen that through the chain 205, the shaft 42 transmits rotation to the sprocket 207 and the sleeve 197, and that rotation of the sleeve 197 is transmitted through the respective sprockets 200 and 201 to the shafts 153 and 172.

In order to support the sleeve 197 in proper spaced relation from the shaft 172, suspension rods 197^a are provided, pivoted to the member 193 and to sleeves 197^b loosely mounted on the shaft 172.

The adjustment of the clutch pins 199 determines whether the sprocket 200 or the sprocket 201 shall be the active driving sprocket and thus determines the speed of the shafts 152, 153 and 172 and the chains 156 and 178 carried thereby.

The first dressing cutters of the sticking unit are operated from motors which are mounted in the following manner:

Slidably mounted on the frame member 158 at each side of the machine is a frame or supporting member 212. Each frame member 212 has a screw-threaded connection with a transversely mounted rod 213, as shown in Figures 17 and 19. The rod 213 is journaled in the end of the frame 158 and has a hand wheel 214 on its end for effecting lateral adjustment of the frame member 212.

Mounted on each frame member 212 inwardly in the machine with relation to the chain 156 is a frame member 215, which supports a motor 216. The frame member 215 is mounted for vertical sliding adjustment on the frame member 212 and its position is varied by means of an adjusting screw 217 mounted in a bracket 218 on the frame 212, as shown for instance in Figure 17.

Mounted on the arbors of the motors 216 are cutters 219 for dressing the outer faces of the stile stock. (Figures 1, 15 and 17.)

The frame member 159 is longer than the frame member 158 in order to support motors 220, as shown in Figure 15. The motors 220 are supported on the frame members 212 laterally adjustable in the machine on the frame member 159 by means of mechanism similar to that described in connection with the mounting of the motors 216.

The motors 220 are directly mounted on vertically adjustable frame members 215,

similar to those described in connection with the motors 216, and similarly mounted and adjustable.

On the arbors of the motors 220 are the 5 cutters 221 for dressing the inner faces of the stile stock.

I have found that I have enough surplus power from the motors 216 to justify operating the pulleys 96 on the shafts 90 hereinbefore described from the pulleys 222 on the shafts of the motors 216 by means of the belts 223.

As the stock passes from the "speed-up" mechanism chains, it is seized between the 15 chains 156 and 178 and carried past the cutter 219 by which the outer face, having the grooves 12 and 13 and hole 11 thereon, is dressed, and then past the cutter 221 by 20 which the inner face is dressed to form the rabbet 14, smooth rib 18, molding 17 and the quirk 19.

I shall now refer to the operation of the machine as a whole, and explain some of the advantages of such a machine. The construction and relative arrangement of the parts will be perhaps made clearer during the explanation of the operation of the machine.

30 Operation of the machine.

In the operation of the machine, a pile of sash stile stock is placed in each hopper. In the right-hand hopper, as illustrated for instance in Figures 1 and 2, the stile is laid 35 with its front face down and its inner face toward the middle of the machine and its top toward the front of the machine. This pile of stile stock in the right-hand hopper will then make right-hand stiles for the sash 40 (as the window is viewed from the inside of a building).

Similarly in the left-hand hopper, the pieces of stock are laid front face down, top toward the front of the machine, and inner 45 face toward the middle of the machine for making left-hand stiles.

The machine is started up and the cam disc 37^a operated in the manner hereinbefore referred to, as illustrated especially in Figure 2, will rotate for bringing the cams 59 between the rollers 37^b for thus swinging the arms 37^c outwardly and effecting the boring operation.

As soon as the cams 59 clear the rollers 55 37^b, the boring drill carriages are drawn back to normal position by the springs 37^a. The disc 37^a is shown in Figure 2 just after the boring operation has been completed.

It may be mentioned in this connection 60 that the hopper frame members 26 and 25 are longitudinally adjustable and the member 27 is adjustable laterally on the machine, so as to adapt the hopper to stock of different sizes.

65 During the boring operation, the roller 76

shown in Figure 5 travels from the point 108 to its full line position shown in said figure without operating the stock pusher bar.

When the boring operation has been completed, the cam face 104 on the periphery of the disc 37^a, shown for instance in Figures 3 and 8, starts between the rollers 101, thus swinging the frames 86 outwardly and moving the cutters 91 and 92 to operative position for cutting the grooves 12 and 13.

The pusher bar actuated by the bar 74, shown in Figure 3, moves forwardly from its position shown in Figure 5 in full lines to its dotted line position shown in said figure for advancing the lower piece of stock to position for the grooving operation.

It will, of course, be understood that the pusher bar mechanisms are employed in duplicate on the opposite sides of the machine 85 for moving the stock out of the hoppers.

At the finish of the forward stroke of the pusher bar, it is speeded up while the roller 76 moves from the position 109 to the position 110, shown in Figure 5.

For advancing the moving stock to position for engagement with the rollers 113 and 125, shown in Figures 2 and 12, these rollers advance the stock and the parts are so geared that the stock is "speeded-up" carried to 95 the rollers 113 and 124 and advanced to the sticking units.

The movement of the stock after it starts to leave the hopper is continuous through the machine.

The stock is advanced by the "speed-up" mechanism to position where it is engaged between the pads 181 on the chains 178 and the chains 156, by which the stock is carried past the face dressing cutters of the sticking unit.

The inner and outer faces are dressed by these cutters and the stock is discharged at the front of the machine.

The machine is more rapid and does 110 faster work than machines that are hand fed.

It is obvious that the automatic feed also does away with considerable labor. The hoppers are readily adjustable for 115 handling all sizes of stock.

The variable speed mechanisms enable the machine to be adapted to such variations in conditions as arise in the factory.

By using double units and sending rights 120 and lefts through the machine at the same time, a number of advantages are secured. The stiles are turned out in pairs and only one counting is necessary. The stiles can be easily stacked in pairs, as they are taken 125 from the machine, which facilitates the handling and reduces the number of handlings necessary and makes it convenient for the further work in completing the window sash. Also by working on the stiles in 130

pairs, it is possible to reduce the amount of mechanism that would be necessary, if two machines were provided, one for making lefts and the other rights.

5 In many instances, single shafts are used for operating the units on both sides of the machine. By operating both boring devices on lefts and rights at once, it is seen that the machine is balanced and that the 10 side pressure on the disk 37^u for instance which would otherwise exist is entirely done away. A single disk 37^u serves to operate both boring devices.

Similarly, a single disc serves to operate 15 both grooving cutter carrier frames.

A single variable speed mechanism serves to operate the units on both sides of the machine.

The sticker unit feed makes it possible to 20 give a straight line travel of the stock regardless of any warping or inequalities, thus permitting straight line cuts by the face dressing cutters.

The unit adjustment of the upper feed 25 chains of the sticking unit allows for ready variation in the capacity of the machine and yet allows a flexible yielding grip for taking care of stock that may be slightly uneven. This also allows for taking up 30 wear in the upper chain guide.

The feed guides are so arranged that they engage the surfaced sides of the stock, thus making it possible to secure more accurate results than when the feed guides engage 35 the unsurfaced faces.

The feed guides or stock advancing devices are so arranged as to carry the stock entirely through without the necessity of pushing one piece of stock by another piece, 40 which allows perfect work at the ends of the stock.

The arrangement of the cutter head of the sticking unit and the guides prevents any undercutting or "dubbing" of the ends 45 of the stock on its way past the cutter heads.

The sticking unit cutters are mounted directly on motor arbors, whereby there is eliminated vibration, the use of belts and space taking machinery and the loss of power.

It is obvious that changes may be made in the construction and arrangement of the parts of my machine without departing from the real spirit and purpose of my invention, and it is my intention to cover by my claims, any modified forms of structure or use of mechanical equivalents, which may be reasonably included within their scope.

I claim as my invention:

60 1. In a machine of the class described, a pair of spaced hoppers, a pair of boring mechanisms arranged between said hoppers, each including a bit, means for imparting rotary motion to the bits in various positions 65 of their longitudinal adjustment, and means

for simultaneously imparting longitudinal movement to the respective bits for boring holes in the lowermost pieces of stock in the respective hoppers.

2. In a machine of the class described, 70 a pair of spaced hoppers, a pair of boring mechanisms arranged between said hoppers, each including a bit, means for imparting rotary motion to the bits in various positions of their longitudinal adjustment, and 75 means for simultaneously imparting longitudinal movement to the respective bits for boring holes in the lowermost pieces of stock in the respective hoppers, said last means including a shaft having a double 80 cam thereon, and operative means interposed between the double cam and the respective boring mechanisms.

3. In an automatic machine of the class described, the combination of a pair of hoppers spaced from each other, a pair of boring mechanisms arranged between the hoppers, and means for successively simultaneously actuating said boring mechanisms for 85 boring holes in the lowermost pieces of stock 90 in the hoppers, means for intermittently simultaneously moving the lowermost pieces of stock out of the respective hoppers, moving mechanisms, and means for simultaneously actuating said moving mechanisms for 95 cutting grooves in the pieces of stock moving from the hoppers.

4. In an automatic machine of the class described, the combination of a pair of hoppers spaced from each other, a pair of boring mechanisms arranged between the hoppers, and means for intermittently simultaneously actuating said boring mechanisms for 100 boring holes in the lowermost pieces of stock 105 in the hoppers, means for intermittently simultaneously moving the lowermost pieces of stock out of the respective hoppers, moving mechanisms, and means for simultaneously actuating said moving mechanisms for 110 cutting grooves in the pieces of stock 115 moving from the hoppers, said first and second described means including a single disc provided with a plurality of cam faces whereby there is secured balanced motion of the respective members of the pairs 115 of the boring and grooving mechanisms.

5. In an automatic machine for making window sash stiles, means for holding successively advanced moving pieces of stock, means for cutting communicating different-sized grooves in each piece while so held, and advancing means for advancing each piece of stock after the grooving operation with a speeded-up movement to a face dressing means for thereafter farther advancing 120 the stock, and means for face dressing the stock during the last advancing movement.

6. In an automatic machine of the class described, a hopper for stock, means for 125 boring a hole in the lowermost piece of stock 130

in the hopper, variable speed means for thereafter sliding said piece lengthwise from the hopper, means for cutting communicating sash cord and sash pulley 5 grooves in said lowermost piece of stock during its movement from the hopper, speed-up mechanism for carrying the stock from the groove cutting means, and means for face dressing the stock after it has been operated 10 on by the speed-up mechanism.

7. In a machine of the class described, a hopper for stock, means for boring a hole in the lowermost piece of stock in the hopper, means for sliding the lowermost piece 15 of stock endwise from the hopper, a guide and receiving means for the stock thus moved from the hopper, means for cutting connected grooves in the piece traveling from the hopper along said guide and supporting means, speed-up mechanism for advancing the stock after the grooving operation has been performed, and means for 20 therenon receiving and face dressing the stock, said mechanism being adapted to advance the stock in a straight line.

8. In a machine of the class described, a hopper for holding sash stile stock in flatwise position, means for boring a hole in the lowermost piece of stock, means for moving the lowermost piece of stock endwise from the hopper, supporting and guide means arranged to receive stock from the hopper, means for grooving the stock thus advancing along the guide means, speed-up 35 mechanism for advancing the stock from the grooving means, and means for thereafter face dressing the stock, the stock being moved in a straight line in flatwise position.

9. In a machine of the class described, means for boring holes in stock, means for advancing the stock from the boring mechanism, means for grooving the stock thus advanced, comprising a relatively wide groove cutter and a relatively narrow groove cutter, means for actuating said groove cutters for causing a wide groove to be cut from the end of the stock for a predetermined distance lengthwise thereof, and for cutting a narrower groove from the wide groove to the bored hole. 40 45

10. In a machine of the class described, a hopper, means for boring holes in the stock in the hopper, means for sliding the stock, one piece at a time from the hopper, means for grooving the stock during said advancing movement, said second means being timed to speed up the advancing movement after the grooving operation and to make a speeded-up return thereafter, to starting 50 55 position.

11. In a machine of the class described, a hopper, means for boring holes in the stock in the hopper, means for sliding the stock, one piece at a time from the hopper, means for grooving the stock during said advancing movement, said second means being timed to speed up the advancing movement after the grooving operation and to make a speeded up return thereafter, to starting 60 65 position, a speed-up mechanism for advancing the stock after the operation of said second means, and means for advancing and face dressing the stock, after the operation of the speed-up mechanism. 70
